UNITED STATES PATENT OFFICE.

LEWIS J. DOUGLASS, OF HARDWICK, VERMONT, ASSIGNOR TO M. WRIGHT & SON COMPANY, OF PUTNAMVILLE, VERMONT, A FIRM.

POLISHING WHEEL.

1,200,926.

Specification of Letters Patent. Patented Oct. 10, 1916.

Application filed August 21, 1915, Serial No. 46,694. Renewed August 24, 1916. Serial No. 116,701.

To all whom it may concern:

Be it known that I, LEWIS J. DOUGLASS, a citizen of the United States, residing at Hardwick, in the county of Caledonia and State of Vermont, have invented certain new and useful Improvements in Polishing-Wheels, of which the following is a specification.

The invention has for an object to effect improvements in polishing wheels such as are used for polishing stone, aiming to increase the efficiency of the wheels and also to prolong the life thereof.

It is an important object to form the wheel with a work engaging face of such a character that the abrasive material used in connection therewith will be held thereunder when in use, and at the same time will cause a uniform utilization of the abrasive over the major part of the area covered by the wheel.

A further important aim is to give an adjustment for the operative connections whereby these may be adjusted with respect to the center of the wheel to compensate for the tendency of such wheels to wear more at one side than at the other which requires wheels to be discarded often before they have given proper length of service, and while there is still a good amount of material in them.

Another purpose is to provide a simple form of construction for an adjustable connection of the character indicated.

Additional objects, advantages and features of invention will appear from the construction, arrangement and combination of parts hereinafter described and shown in the drawings, in which—

Figure 1 is a fragmentary top view of a grinding wheel, Fig. 2 is a fragmentary perspective view thereof, Fig. 3 is a bottom view thereof, Fig. 4 is a vertical sectional view on the line 4—4 of Fig. 3.

There is illustrated a wheel 10 which may be used with any of the familiar machines for polishing stone now generally in use, the construction of which is sufficiently well known to require no illustration. It comprises a circular disk or top plate body portion 11 of a size and thickness corresponding to that of similar parts in wheels generally

used, and upon its lower side there are provided two scroll flanges 12 each starting closely adjacent the outer edge of the disk 11 at diametrically opposite points and extending over a radius of approximately two hundred and sixty-five degrees with respect to the center of the disk, leaving a large approximately circular space 13 between them in which are located a number of L-shaped flanges in nested sets, as at 14 and 15. The end portions of each of these flanges are disposed at an angle of approximately one hundred and thirty-five degrees to each other.

It will be noted that the inner ends of each scroll flange are overlapped with the outer end of the other a short distance, forming a channel 16 at each side of the wheel, the flanges being spaced from each other. The flanges 14 and 15 are similarly spaced from each other, and the sets are respectively positioned so that the ends of the flanges therein are disposed closely adjacent the inner ends of the channels 16, the ends of some of the flanges 14 and 15 being disposed in line with the passages. The outermost flanges 14 and 15 are spaced somewhat closer to respective scroll flanges than the width of the channels 16, although this is not invariable. The ends of the flanges 14 and 15 farthest from the respective adjacent channels 16 stop short of the flanges at the adjacent sides of the disk.

On the top side of the wheel diametrical channels 18 and 19 are formed centrally of the wheel and at right angles to each other, the sides of these channels being formed by V-shaped ribs 20 cast integrally with the disk 11 located on respective quarters of the disk, their opposed sides being under-cut as at 21 in Fig. 2. A pivot plate 22 is provided, shaped and proportioned to engage snugly and slidably in either of the channels 18 and 19. This plate is provided with two ears or lugs 23, having registered openings 24 therethrough, the lugs being centrally located on the plate 22 and spaced and proportioned suitably for engagement with the usual rotating connections of polishing wheels. The plate 22 extends a considerable distance outwardly of these lugs at each end, for a reason which will appear, and inter-

mediately of each end portion of the plate a binding screw 25 is engaged therethrough, adapted to bear against the bottom of the channels 18 or 19 when the plate is engaged 5 therein.

In use, the plate 22 is initially adjusted in either of the channels 18 and 19 with the lugs 23 equally spaced from the center of the wheel 10. If the wheel wears unevenly, 10 one side becoming worn more than the other, the tendency is for the worn side to wear at an increased rate while the thicker side wears at a decreased rate. The wheel being unbalanced also has an irregular movement, 15 putting an increased strain on the driving connections and decreasing its polishing efficiency. When the beginning of such wear is discovered, by adjusting my plate 22 so that the ears 23 are moved toward the 20 thicker side of the wheel, the wheel is balanced and the tendency to uneven wear corrected.

In rotating upon the work the scroll channels serve to hold the abrasive material under the wheel, while the flanges 14 and 15 utilize the material efficiently without tending to gather it toward the center in an objectionable quantity. By the off-set relation of the two sets of L-shaped flanges, the abrasive under the central major body portion of the wheel is utilized over and over, being moved first one way and then another. One end of each flange 14 or 15 tends to pull the material inward, while the other end 35 tends to throw it outwardly.

It is obvious that my wheels can be quickly mounted and dismounted, and the pivotal connections with the driving means may be permanent, it being only necessary 40 to loosen the set screws 25 and slip the plate 22 from between the ribs 20 for removal of the wheel.

The manufacture of my wheel is quite simple and involves no greater expense than

the production of the ordinary wheel generally used. 45

What is claimed:

1. A wheel of the class described comprising a top body portion having two diametrical intersecting channels formed thereon, 50 a plate shaped to fit snugly in the channels alternatively, means to form operative connections with the wheel centrally of the plate, and means to fix the plate to the body. 55

2. A wheel of the class described comprising a top plate body, a plurality of scroll flanges on the under side thereof adjacent the edge, stopping short of the center a considerable distance whereby a large space is left inwardly thereof, and a multiplicity of 60 separate L-shaped flanges in nested relation but spaced a part within said space the last named flanges being so positioned that a portion of each will engage particles of abrasive material under rotation of the 65 wheel at a greater angle of incidence than the scroll flanges, and certain other portions thereof will ward material engaged outwardly.

3. An abrading wheel comprising a top 70 plate body, scroll flanges thereon adjacent the edge for inward draft of abrasive, the scroll flanges terminating close to the edge of the plate, respective sets of nested L-shaped flanges on the plate within the 75 scroll flanges having rectilinear portions at each end and having their angular apices presented outwardly on the plate, the ends of each set in the direction of rotation being located close behind the inner terminations 80 of respective scroll flanges.

In testimony whereof I have affixed my signature in presence of two witnesses.

LEWIS J. DOUGLASS.
